Fraunfeld and Richards

UNITED STATES PATENT OFFICE.

RUSSELL WHITCOMB, OF ELIZABETH, NEW JERSEY.

CONTAINER.

1,362,975.

Specification of Letters Patent. Patented Dec. 21, 1920.

Application filed June 9, 1919. Serial No. 302,917.

To all whom it may concern:

Be it known that I, RUSSELL WHITCOMB, a citizen of the United States, residing at Elizabeth, in the county of Union and State

5 of New Jersey, have invented certain new and useful Improvements in Containers; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 The present invention relates, generally, to containers for cosmetic sticks, soap sticks and similar articles; and the invention has reference, more particularly to a novel construction of sanitary refillable container 20 having a novel means for holding and advancing the contents ready for use.

The invention has for its principal object to provide a novel construction of refillable carrier and protective covering for cosmetic 25 sticks, and the like, which serves not only to protect the contents from dirt, germs, etc., when carried about, but also provides a means for handling the contents, without necessity of touching the same with the 30 fingers, when making ordinary use and application of the contents, consequently providing a very sanitary and hygienic container. The container also comprises an arrangement of parts which may be quickly 35 and easily sterilized by dipping in hot water.

The invention has for a further object to provide, in connection with a suitable enveloping casing, a means for gripping and holding the contents relative to the casing 40 so that the same may be easily advanced or fed upward out of the casing as the same is used without necessity of touching the contents with the fingers; and, furthermore, the invention has for another object, to provide a gripping and holding element which permits of the contents to be refilled in behind the stub of the almost consumed stick, so that the latter continues to be fed forward from behind until entirely consumed, 45 this being accomplished without necessity for touching or removing said stub from the gripping or holding device, but merely by inserting the new stick in the latter behind the stub of the old. Said gripping and holding device being further constructed to permit the engaged stick to be readily and easily

advanced in a projecting or forward feeding direction, while holding the same firmly against backward movement or retraction through said holder or gripping device. 60

Other objects of the present invention, not at this time more particularly enumerated, will be clearly understood from the following detailed description of the same.

With the various objects of my present 65 invention in view, the same consists, primarily, in the novel container for cosmetic and soap sticks, and the like, hereinafter set forth; and the invention consists, furthermore, in the various arrangements and combinations of the several devices and parts, as well as in the details of the construction 70 of the same, all of which will be more fully described in the following specification, and then finally embodied in the claims which 75 are appended thereto.

The invention is clearly illustrated in the accompanying drawings, in which:—

Figure 1 is a side elevation of the novel construction of container made according 80 to and embodying the principles of my present invention, the cover portion being partly broken away and shown in section.

Fig. 2 is a longitudinal transverse section, taken on line 2—2 in said Fig. 1. 85

Fig. 3 is a front elevation of the container, with the cover portion removed and shown in part elevation and part section.

Fig. 4 is a central longitudinal vertical section. 90

Fig. 5 is a cross-section taken on line 5—5 in said Fig. 4, the stick and gripping or holding device therefor being shown in elevation.

Fig. 6 is a perspective view of the stick 95 and gripping or holding device therefor, removed from the container.

Similar characters of reference are employed in all of the hereinabove described views, to indicate corresponding parts. 100

Referring now to the said drawings, the reference-character 1 indicates the complete novel container for cosmetic or soap sticks, and the like, the same comprising a tubular main body 2 having a closed end wall 3 at its lower or bottom end, but open at its upper or top end. The reference-character 4 indicates a cover member having a closed end wall 5 at its upper or top end, but open at its bottom end to permit the same to be 105 telescopically engaged over the upper or top end of said main body 2. 110

The reference character 6 indicates a stick gripping and holding device comprising a short sleeve split at one side throughout its length to provide free longitudinally extending edges having formed therein a plurality of slightly inwardly and upwardly inclined serrations or teeth 7. Connected with said sleeve 6 is an outwardly and laterally protecting shank 8 having at its free end a button or head 9 providing a manipulating finger piece.

The reference character 10 indicates a stick of cosmetic, such as a lip-stick, eye-brow pencil, or a stick of soap such as a shaving stick, or the like. The stick 10 is inserted through the sleeve 6 from the lower end, and pushed upwardly therethrough to project its upper end a short distance above the upper extremity of said sleeve 6. The serrations or teeth 7 will not prevent or impede the upward movement of the stick 10 through the sleeve 6 when the sleeve is held in the fingers and the lower end of the stick is pressed against a stationary surface to impart an upward movement thereto through the sleeve, but said serrations or teeth will impede a downward or retractive movement of the stick through the sleeve, since the inwardly and upwardly inclined points or projections afforded by the teeth will dig into the surface of the stick to arrest such movement. It must be understood that I do not wish to limit myself exactly to the shape and number of the serrations or teeth 7, as shown in the drawings, since the same may be varied in such respects according to the convenience of the maker of the container.

After the stick 10 has been assembled in gripped relation to the gripping or holding device the same is inserted within the main body 2. The wall of said main body 2 is provided with a short downwardly extending longitudinal slot 11, which receives the shank 8 of the finger piece of the gripping or holding device, as the same moves into the open end of said main body 2. It will be noted that said slot is of short extent compared with the entire longitudinal extent of said main body 2, and that it is open at its upper end. The length of the slot 11 is necessarily shorter than the length of the cover member 4, so that when the finger piece is stopped by engagement with the lower end of the slot 11, and the cover member 4 engaged over the main body 2, the slot 11 will be entirely closed over by the cover member. The length of the slot 11, however, is sufficient to permit the finger piece 9 to be raised therein for the purpose of lifting the gripping or holding device a sufficient distance to project above the upper end of the main body 2, the forward or upper end of the stick, so that the same is

sufficiently exposed or projected to permit the user to make application of the stick to her or his person.

The cover member 4 is provided in its wall with a longitudinal slot 12 at its open end, said slot being open at its lower end and extending upwardly for a sufficient length to receive and straddle the shank 8 of the finger piece 9, when the cover is closed or engaged over the upper end of said main body 2. As shown more particularly in Figs. 75 1, 2 and 4, it will be apparent that when the cover member is engaged in closed relation to the main body 2, the slots 11 and 12 will respectively straddle the shank 8 of the finger piece 9, so that all openings leading 80 into the container are closed against the entrance of dust, dirt or other foreign substances, and that consequently the container is entirely closed in enveloping relation to the stick 10, and adequately protects the 85 same from the sanitary and hygienic standpoint.

As the stick 10 is worn down in use the same may be quickly advanced in the holding or gripping device by removing the latter from the main body 2, and by grasping the holding or gripping device, without touching the stick with the fingers, and by then pressing the lower end of the stick against a stationary surface, the stick may 95 be pushed upward through the holding and gripping device an advanced distance. Ordinarily the stick is advanced but a short distance beyond the upper end of the holding and gripping device, so that by merely 100 manipulating the finger-piece 9 to raise the same in the slot 11, the holding or gripping device is raised sufficiently to project the upper end of the stick beyond the end of the main body 2, and exposed for use.

Another advantage of the holding or gripping device, is that it provides a means for holding the stick 10 in such a way that as the same is worn down to a butt or stub, a new stick may be inserted behind the butt 110 or stub to be fed up in a "follow after" relation to the butt or stub, the latter being fed out by the following new stick until said butt or stub is entirely consumed. It will thus be apparent that the butt or stub does 115 not have to be removed or handled in any way when inserting a refill or new stick, and in respect to what may be termed the "follow after" method of inserting refills in the holding or gripping device, I have devised a holding means for combination with the enveloping container which is very superior to all devices or containers which require the removal of the stub or butt of the old stick from the holding or gripping device, so that the new stick may be secured to the latter, and which further requires the securing of the stub or butt of the old stick 120 125

upon the forward end of the new stick, in order to render said stub or butt capable of further use.

When the sticks of cosmetics or soap are enveloped in oiled paper, tin-foil or other similar covering, they are applied, fed and refilled in the same manner as above described, and the top annular edge 13 of the holding or gripping device serves as a gage or shear edge against which the covering material may be cut or parted when removing the same from the outwardly or upwardly projected portion of the stick.

It will be apparent that my novel construction of container provides a very efficient protection of the stick enveloped thereby, against contact with dirt, dust or the fingers, and consequently serves admirably to maintain the same in perfect sanitary condition. The container itself may be easily and quickly sterilized by removing the holder or gripping device and the stick carried thereby, and then dipping the main body 2 and cover member 4 in boiling water. The holding or gripping device and stick, where the character of the latter will allow it, may also be sterilized by quickly dipping the same in hot water, all of which aids in maintaining an adequate sanitary and hygienic condition as to said parts.

I am aware that some changes may be made in the several novel arrangements and combinations of the several devices and parts as well as in the details of the construction of the same, without departing from the scope of my present invention as described in the foregoing specification and as described in the appended claims. Hence, I do not limit my invention to the exact arrangements and combinations of the various devices and parts as set forth in the foregoing specification, nor do I confine myself to the exact details of the construction of said parts as illustrated in the accompanying drawings.

I claim:

1. A container for toilet preparations in stick form comprising a tubular main body closed at its lower end, a cover member engageable over the open end of said body, a removable stick holding means associated with said body comprising a longitudinal sleeve having open ends whereby a stick may be fed upwardly therethrough and permitting a refill stick to be inserted through the lower end of said sleeve behind the butt of the old stick and fed upwardly thereafter until said butt is consumed and the new stick exposed, a finger piece projecting laterally from the body of said sleeve, and said main body having a longitudinal open ended slot extending downwardly from its open mouth into which said finger piece may pass to ride therein.

2. A container for toilet preparations in stick form comprising a tubular main body closed at its lower end, a cover member engageable over the open end of said body, a removable stick holding means associated with said body comprising a longitudinally split sleeve having open ends whereby a stick may be fed upwardly therethrough and permitting a refill stick to be inserted through the lower end of said sleeve behind the butt of the old stick and fed upwardly thereafter until said butt is consumed and the new stick exposed, and the free longitudinal edges of said split sleeve having inwardly and upwardly inclined teeth to hold said stick against downward movement while permitting upward feeding movement thereof.

3. A container for toilet preparations in stick form comprising a tubular main body closed at its lower end, a cover member engageable over the open end of said body, a removable stick holding means associated with said body comprising a longitudinally split sleeve having open ends whereby a stick may be fed upwardly therethrough and permitting a refill stick to be inserted through the lower end of said sleeve behind the butt of the old stick and fed upwardly thereafter until said butt is consumed and the new stick exposed, the free longitudinal edges of said split sleeve having inwardly and upwardly inclined teeth to hold said stick against downward movement while permitting upward feeding movement thereof, a finger piece having a shank projecting laterally from the body of said sleeve, and said main body having a longitudinal slot extending downwardly from its open end into which said shank of said finger piece may pass to ride therein, said cover member being adapted to close over said slot when said finger-piece is drawn down to the lower limit of the same.

4. A container for toilet preparations in stick form comprising a tubular main body closed at its lower end, a cover member engageable over the open end of said body, a removable stick holding means associated with said body comprising a longitudinally split sleeve having open ends whereby a stick may be fed upwardly therethrough and permitting a refill stick to be inserted through the lower end of said sleeve behind the butt of the old stick and fed upwardly thereafter until said butt is consumed and the new stick exposed, the free longitudinal edges of said split sleeve having inwardly and upwardly inclined teeth to hold said stick against downward movement while permitting upward feeding movement thereof, a finger-piece having a shank projecting laterally from the body of said sleeve, said main body having a longitudinal slot extend-

ing downwardly from its open end into which said shank of said finger piece may pass to ride therein, said slot being of a length slightly less than the length of said cover member, and said cover member having a longitudinally indented slot at its open end adapted to straddle said shank of said finger-piece when said cover member is in closed relation to said main body and said

finger-piece is drawn down to the lower 10 limit of the slot of the latter.

In testimony that I claim the invention set forth above I have hereunto set my hand this 4th day of June, 1919.

RUSSELL WHITCOMB.
